SAFETY FEEDING DEVICE FOR WRINGERS

Huyett H. Gaines, Los Angeles, Calif.

Application April 12, 1933. Serial No. 665,661

5 Claims. (Cl. 68—32)

This invention relates to safety feed devices for roll wringing mechanism.

One of the objects of the invention is in the provision of a safety feeding device for roll wringing mechanism so arranged as to permit the automatic feeding of garments to the wringer rolls without danger to the operator's hands.

Another object is in the provision of a safety feeding device which comprises an apron member disposed adjacent the wringer rolls and driven thereby, said apron member operating to continuously feed the garments placed thereon into the wringer rolls, and thereby obviating any possibility of injury to the operator's hands.

Still another object is in the provision of a safety feeding device composed of an angularly disposed apron or feeding portion which is driven by frictional contact with the wringer rolls, said apron member having a quick detachable connection which permits its ready placement upon either side of the wringer to accommodate the operator in any of the washing operations.

A further object is in the provision of a safety feeding device for roll wringing mechanism which includes an apron member, a support and framing means therefor and a detachable suspending means for the apron, which permits the apron to frictionally contact the rolls by gravity and to be driven therefrom.

A still further object is in the provision of a detachable safety feeding apron mechanism which is driven by frictional contact with the wringer rolls, the detachability of the safety feeding device permitting its ready removal from the wringer and therefore insuring ease in shipment.

An additional object is to provide an apron type safety feeding mechanism having means for automatically engaging and operating a water shed member whereby water falling from the wringer rolls is diverted toward the side of the wringer to which my feeding device is attached.

Another object lies in the provision of an apron type of safety feeding mechanism for roll wringing devices, said apron member including driving mechanism comprising roller members frictionally contacting the movable wringer rolls and through certain driving mechanism operating the apron in such manner as to present the garments placed thereon directly to the wringer rolls without any possibility of injury to the operator's hands, said safety device not only having quick detachable mounting but also being so suspended upon the wringer in a manner to enhance the over-all appearance of the wringer and washer upon which it is mounted.

Other objects will appear in the following specification, taken in connection with the annexed drawings, in which—

Fig. 1 is a perspective view of a conventional wringer with my feeding device attached; 60

Fig. 2 is an end elevational view with certain portions broken away to permit a clearer view of underlying parts;

Fig. 3 is a fragmentary view, partly in section, taken from line 3—3 in Fig. 5, showing details of 65 structure to be described;

Fig. 4 is a view showing details of driving roller structure to be described;

Fig. 5 is a plan view of my feeding device mechanism; 70

Fig. 6 is a side elevational view of the same;

Fig. 7 is an end elevational view of the device as the same might be seen from the left in Fig. 5;

Fig. 8 is a sectional view taken from line 8—8 75 in Fig. 5;

Fig. 9 is a sectional view taken from line 9—9 in Fig. 5;

Figs. 10 and 11 are end views of the wringer mechanism showing the method of attaching and 80 detaching the feeder to be described.

Before referring to the specification for a detailed description of the invention, applicant desires to call attention to several classes of safety devices which are well known to the trade.

The ordinary type of safety mechanism for roll wringing devices comprises a safety release mechanism which is adapted to be manually struck by the operator, which in turn results in the explosion of the wringer and consequent release of tension between the rolls. Many and varied attempts have been made to dispose this manually operable safety release member in such position as to absolutely insure explosion of the wringer. However, a safety device of this character is adapted to be operated following an 95 injury.

Again, we find various types of chutes and roller mechanisms upon which the garments are adapted to be placed by the operator for presentation to the rolls. However, it is believed that 100 applicant, for the first time, presents a safety feeding device which has the practical advantage of detachability necessary in the shipment of the wringer and also the additional advantage of being power driven from the wringer itself to the end that the garments will be continuously 105 and automatically conveyed to the wringer rolls without necessity of the operator's placing his hands in any proximity whatsoever to the moving wringer rolls.

Referring to the drawings, Fig. 1 discloses a conventional wringer structure generally designated as 10. Since the invention herein described comprises an attachment for wringers, which may 5 be of any make or type, it is thought unnecessary to describe the wringer structure further than to say that the device comprising my invention is attached to a wringer by means of hooks 11 which are secured to end portions of the frame thereof 10 as indicated in Figs. 1 and 2, and further that the wringer is provided with a rockable water shed member 10' which is adapted to be engaged and operated by a portion of my feeding device, as will be described.

15 Figs. 5, 6 and 7 will indicate that my feeding device comprises a pair of housings 12 generally comprising cupped inner portions 12' having outer cover members 12'' secured thereto. The housings are joined by means of a plate 13, 20 the whole forming a substantial framework suitable for supporting a roller and apron mechanism which will now be described.

Fig. 5 will indicate that an apron member 15 is supported between housings 12 upon plural 25 rollers 16 and 17.

As indicated in Fig. 3, the rollers 16 and 17 comprise body portions 18 made from wood or other suitable material, to either end of which is secured ferrule members 19, the same having 30 integrally formed flange portions 20 and trunnion portions 21. As clearly shown in the several views, the rollers are somewhat contracted at their ends and this, together with flanges 20, provides suitable trackage for apron 15.

35 Rollers 16 and 17 are supported in housings 12 by means of the trunnions 21 journaled in bearings 22 formed in the inner surface of the housing members 12'.

Within the larger lower ends of each of housings 12 are friction wheels 23 rotatably supported 40 in the housings by means of pins 24, the wheels being mounted upon the pins by means of hubs formed by extending boss portions 25 of pinions 26 which occupy cavity portions 27 of the wheels.

45 The pins 24, pinions 26 and wheels 23 are secured into a unit assembly by means of pins 28 which pass through the three members as shown.

The friction wheels have an outer facing 29 composed of rubber or other suitable friction 50 material and are freely rotatable in bearings 30 formed in housing members 12' and 12''.

The trunnions 21 of roller 16 have pinions 31 55 removably secured to the latter and these are adapted to mesh with pinions 26 of wheels 23 as shown.

In view of the foregoing, it will be clear that rotation of wheels 23 will result in rotation of roller 16 in the opposite direction, with corresponding movement of apron 15 and rotation 60 of roller 17. This feature will be referred to shortly.

Figs. 5, 6 and 7 will illustrate ear or bracket members 32 secured to either of housings 12 and extending generally outwardly and upwardly 65 therefrom.

In the uppermost portion of the brackets are secured studs 33.

Mention of hooks 11, as secured to the wringer frame, has already been made.

70 Reference to Figs. 1 and 2 will show that studs 33 are adapted to engage in hooks 11 to form a support for the mechanism whereby the mechanism is pivotally supported adjacent the wringer rolls in such a manner that the weight of the 75 device is available to maintain friction wheels

23 in pressure contact with the lower roll of the wringer.

The plural hooks 11 provide means for attaching the feeder to the wringer in several angular positions as indicated in dotted lines in Fig. 2. 80 Thus the feeder may be adjusted to meet requirements of practical use.

Considering the foregoing description, it will be apparent that removal and replacement of apron 15 may quickly be accomplished by removal of a cover member 12'' from one of the end housings 12, exposing the underlying friction wheel 23 which may then be removed, exposing pinion 31 which may then be withdrawn from trunnion 21 whereupon housing portion 12' may be removed from the trunnions exposing the ends of rollers 16 and 17 to permit removal and replacement of the apron. Reassembly is accomplished by manipulation of the parts in reverse order.

It is thought that the foregoing has described the structure and operation of my feeding device sufficiently to obviate further description; however, operation of the device may be summarized by saying that with my device attached 100 as shown in Figs. 1 and 2, rotation of the wringer rolls in the direction of the arrows will, through friction between the lower wringer roll and wheels 23, cause corresponding rotation of roller 16 to move the upper surface of apron 15 toward the wringer rolls. With the wringer rolls rotating as shown, the apron is adapted to conduct materials toward and into the wringer, whereby the materials may be satisfactorily fed to the wringer without need for an operator's 110 hand to be placed near to or in contact with the wringer rollers.

Thus, my feeding device provides a means whereby materials may be fed to a wringer with perfect safety to both the operator and materials.

The view shown in Fig. 8 will indicate the relative positions of friction wheels 23 and roller 16. The relative speed ratio between the wringer roll and roller 16 is such that the apron surface 120 moves at suitable speed relative to the peripheral speed of the wringer rollers.

It will be noted that by this arrangement the friction wheels which engage the lower wringer roll are located beyond the edges of the apron. 125 This makes the device more satisfactory inasmuch as clothes which are within the confines of the apron itself cannot be caught between the wringer rolls and the friction rolls.

A water shed member 10' has already been 130 noted as attached to the wringer mechanism.

Fig. 2 illustrates portions 12''' extending downwardly from housing members 12' in such a manner as to engage the rockable water shed member to maintain the same in position as 135 shown in Fig. 2, whereby water falling from the rolls or feeder is automatically diverted back to its source.

Figs. 10 and 11 illustrate the convenience with 140 which the feeder may be attached to a wringer.

Fig. 10 shows the feeder about to be attached, with extensions 12''' engaged with water shed 10', while Fig. 11 indicates continued manipulation to further operate the water shed plate 145 and simultaneously bring studs 33 into position to engage hooks 11, also to bring friction wheels 23 into contact with the wringer roll. Further manipulation places the parts in working position shown in Fig. 2.

What I claim is:

1. A safety feed mechanism for roll wringers having a feeding apron and supporting frame therefor, the apron adapted to be driven by means of contact of members of the apron mechanism with one of the wringer rolls, means for detachably supporting the apron mechanism upon the wringer in such a manner that the mechanism may be attached to either side of the wringer in adjustable angular relation thereto, and means associated with the feed mechanism to engage and operate water deflecting mechanism whereby the water deflecting mechanism is automatically positioned to deflect water toward the side to which the feed mechanism is attached. 5
2. A safety feed mechanism for roll wringer mechanisms comprising dual apron rollers, apron member supported thereon, supporting frame therefor comprising end members and connecting portion, means for driving the apron member comprising supplementary rollers supported in said end frame members, the rollers having driving connection with one of the apron rollers, bracket members secured to said end frame members, said bracket members including hook portions, separate hook members adapted to be secured to the wringer mechanism to cooperate with said bracket hook portions to support the feed mechanism in such a manner that the sup- 10
- plementary rollers lie in contact with one of the wringer rolls, whereby rotation of the wringer rollers imparts rotation and feeding movement to the apron member. 15
3. A safety feeding device for a roll wringer comprising a frame, means to support said frame on the wringer, a pair of apron rolls mounted in said frame, an apron carried by said rolls, and means located beyond the edge of the apron frictionally engaging one of the wringer rolls, and means connected to said engaging means to drive said apron. 80
4. A safety feeding device for a roll wringer comprising a pair of casings, means holding said casings in spaced relation, a pair of apron rolls mounted in said casings, an apron on said rolls between said casings, means to support said casings on a wringer, and means in one of said casings frictionally engaging one of the wringer rolls to drive said apron. 85
5. A safety feeding device for roll wringing mechanism comprising an apron mechanism and support, framing means therefore whereby the apron mechanism will be supported adjacent the roll and frictionally driven thereby, and means whereby water deflecting mechanism of the wringer mechanism is automatically operated and maintained to deflect water toward the side to which the apron mechanism is attached. 90
